UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

CEILING FAN.

Original application filed November 4, 1918, Serial No. 260,968. Divided and this application filed January 8, 1923. Serial No. 611,262.

My invention relates to ceiling fans and in particular to ceiling fans having slowly rotating fan members.

Heretofore, it has been customary, in manufacturing ceiling fans of the above character to employ a large slow-speed motor or, in gyratory fans, to employ a plurality of small high-speed motors. It is the principal object of my invention to provide 10 a fan with a novel driving connection whereby a single small high-speed motor may be employed to drive either a gyratory fan or a ceiling fan of the type employing large fan blades at a relatively slow speed. A further object of my invention is to provide 15 means whereby the angular position of the driven fan members may be readily adjusted.

In the accompanying drawings, Fig. 1 is a sectional view of one form of my invention 20 embodied in a ceiling fan of the stationary type; Fig. 2 is a detail view showing the driving mechanism employed in the fan illustrated in Fig. 1; Fig. 3 is a sectional view of my invention embodied in a ceiling fan of the large-blade type; Fig. 4 is a 25 view, partially sectional and partially elevational, of my invention embodied in a gyratory ceiling fan; and Figs. 5 and 6 are detail views, with parts broken away for the 30 sake of clearness, of the driving mechanism employed in the structure shown in Figs. 3 and 4, respectively.

Referring to Fig. 1, I show a fan comprising a motor 1 and a plurality of sets of fan blades 2 mounted on supporting arms 3 that project from said motor 1. The motor consists of a stator member 4, a casing 5 therefor, a stationary shaft 6, and a rotor member 7 mounted upon a sleeve 8 which, in turn, is rotatably mounted upon, and supported by, the stationary shaft 6. The fan-supporting arms 3 are stationary and are mounted on the lower end of the shaft 6. The sleeve 8 is provided with a spiral gear 9 at its lower end to mesh with spiral gears 10, provided on the ends of the shafts 11 which are encased within the arms 3 and rotate the fan blades 2, as best shown in Fig. 2. In a construction, such as shown in Figs. 50 1 and 2, a speed reduction may be obtained by making the spiral gear 9 with a smaller number of teeth than the spiral gears 10.

In Fig. 3, I show a motor similar to that shown in Fig. 1 but provided with a ceiling

fan 12 of the large-blade type. In this type 55 of fan, the worm 9 on the high-speed sleeve 8 drives a worm gear 13. The worm gear 13 is rigid with a worm 13' which drives a worm gear 14 having a worm 14' that meshes with a worm 15 of the stationary shaft 6. 60 This driving mechanism is clearly illustrated in Fig. 5 of the drawing. The fan blades 12 are mounted upon a slow-speed sleeve 16 which also serves as a bearing for the shaft of the worm 13'. It will be obvious to those skilled in the art that the tendency of the worm 14 to turn the shaft 6 65 will cause the blades 12 to rotate about the shaft 6, at a relatively low speed.

It will be readily understood that any desired speed reduction may be obtained by making the worms 19 and 13' and worm gears 13 and 14 with the proper teeth ratios. Consequently the casing 16 and blades 12 may be made to rotate at any desired speed 75 relative to the sleeve 8.

In the gyratory fan shown in Fig. 4, and the relating detail Fig. 6, the worm 9 on the high-speed sleeve drives worm gears 16' on shafts 17. The shafts 17 have worms 17' 80 thereon which, in turn, through worm-gears 25 rotate shafts 18, and the latter drive fan shafts 11 by means of worms 18' on shafts 18 meshing with worm gears 11' on shafts 11. One of the shafts 17 also drives a worm-threaded shaft 19 by means of helical gears 19^a and 19^b. The shaft 19 operatively engages the worm 15 of the shaft 6, and causes rotation of the fan sets about the shaft 6. The fan-supporting arms are mounted upon 90 the slow-speed sleeve 16 which forms bearings for the shafts 17, 18 and 19. By means of this drive I obtain a relatively low speed of rotation of the individual fans and still lower speed of rotation of the fan-carrying 95 member 16. In this embodiment of the invention the speed reduction is effected by a worm and worm gear drive, the worm being mounted on the driving member. Therefore a train of gears may be provided for 100 revolving the fan sets at any desired speed as they rotate.

The position of each of the fan sets is adjusted independently by means of a set screw 21, as best shown in Fig. 4, which moves the fan-supporting arm 11 about the axis of the worm-threaded shaft 18 as an axis.

The lubrication system, as best shown in

Fig. 4, comprises an oil reservoir 22 at the lower end of the shaft 6 and an additional reservoir 23 disposed at the junction of the high and low-speed sleeves 8 and 16, thus insuring a supply of oil at that important point. The shaft 6 is provided with helical grooves 24 whereby the oil is carried vertically along the shaft to a chamber 25 from which it drains back into the reservoir 23 by means of a passage 26. Oil, overflowing from the reservoir 23, drains into the reservoir 22, thus preventing the dripping of any oil therefrom.

While I have shown my invention in a plurality of forms, it will be obvious to those skilled in the art that it is not so limited but is susceptible of various minor changes and modifications without departing from the spirit thereof, and I desire, therefore, that only such limitations shall be placed thereupon as are imposed by the prior art or are specifically set forth in the appended claims.

I claim as my invention:

1. In an electric fan, in combination, a motor provided with a stationary shaft and a rotor rotatably mounted on the shaft, a plurality of fan wheels disposed to revolve about the shaft, a drive interposed between the fan wheels and rotor for rotating the fan wheels about their respective axes, and means actuated by the drive co-operative with the shaft to move the fan wheels in a predetermined path as they rotate.

2. In an electric fan, in combination, a motor provided with a stationary shaft and a rotor rotatably mounted on the shaft, a plurality of fan wheels disposed to revolve about the shaft, a drive interposed between the fan wheels and rotor for rotating the fan wheels about their respective axes, said drive being adapted to revolve about the axes of the motor shaft, and means actuated by the drive co-operative with the shaft to move the fan wheels in a predetermined path as they rotate.

3. In an electric fan, in combination, a motor provided with a stationary shaft and a rotor rotatably mounted on the shaft, a plurality of fan wheels disposed to revolve about the shaft, a drive interposed between the fan wheels and rotor for rotating the fan wheels about their respective axes, a worm fixed to the motor shaft and a train of gears actuated by said drive disposed to engage said worm co-operative to give the fan wheels a circulatory movement as they rotate.

4. In a ceiling fan, a plurality of sets of fan blades and a motor consisting of a stator comprising a magnetic field frame and a worm-threaded shaft, and a rotor comprising an armature mounted on a worm-threaded sleeve concentrically mounted upon and supported by said shaft, and threaded means coating with said sleeve and said shaft to cause rotation of said individual fan sets and also to cause rotation of said sets about said shaft as an axis.

5. In a ceiling fan, a plurality of sets of fan blades and a motor consisting of a stator comprising a magnetic field frame and a worm-threaded shaft, and a rotor comprising an armature mounted on a worm-threaded sleeve concentrically mounted upon and supported by said shaft, and threaded means coating with the threaded portions of said shaft and of said sleeve to cause rotation of said individual fan sets and also to cause rotation of said sets about said shaft as an axis.

6. In a ceiling fan, a plurality of sets of fan blades and a motor consisting of a stator comprising a magnetic field frame and a worm-threaded shaft, and a rotor comprising an armature mounted on a worm-threaded sleeve concentrically mounted upon and supported by said shaft, and additional worm-threaded shafts driven by said sleeve and driving said individual sets of fans, one of said additional shafts engaging a worm-threaded shaft which engages the threads on said first named shaft to cause rotation of said sets of fans about a common axis.

7. In a ceiling fan, a plurality of sets of fan blades and a motor consisting of a stator comprising a magnetic field frame and a worm-threaded shaft, and a rotor comprising an armature mounted on a relatively high-speed worm-threaded sleeve concentrically mounted upon and supported by said shaft, and a relatively low-speed sleeve concentrically mounted on said shaft in end-to-end relation with said high-speed sleeve, and worm-threaded shafts driven by said high-speed sleeve and rotatably connected to said fan sets, and an additional worm-threaded shaft engaging one of the said driven worm-threaded shafts and engaging the stationary shaft, said slow-speed sleeve forming bearings for said worm-threaded shafts.

8. A fan mechanism comprising a single driving motor, a plurality of supporting arms pivotally mounted thereon, a plurality of fan sets mounted on said arms, worms mounted on said motor structure and operatively associated with said motor and having their rotative axes coincident with the pivotal axis of said supporting arms, and additional worms mounted on said supporting arms in engagement with said first named worms and operatively associated with said fan sets.

In testimony whereof, I have hereunto subscribed my name this second day of January, 1928.

CHRISTIAN AALBORG.
